APPARATUS FOR AND METHOD OF FOLDING
AND STITCHING NECKTIESJames F. Baker, Troy, and Arthur E. La Mora,
Cohoes, N. Y., assignors to Cluett, Peabody &
Co., Inc., Troy, N. Y., a corporation of New York

Application June 28, 1943, Serial No. 492,520

6 Claims. (Cl. 112—2)

This invention pertains to the manufacture of four-in-hand neckties, and relates more particularly to a novel method of and apparatus for folding and stitching such ties.

In accordance with one customary practice, the necktie blank is folded wrong side out to form two superposed plies and at widely spaced intervals, located along a line located somewhere between the line of fold and the free edges of the plies, the plies are united by tacking stitches. For instances, the plies may be thus united at nine points substantially equidistant apart and disposed along a line approximately half-way between the free edges and the fold. After this tacking operation the tie is turned right side out.

This folding and sewing operation may be performed by hand but requires a considerable degree of skill on the part of the operator in order that the tie may be folded properly and uniformly, and so that when turned it will be of accurate width, smooth and with the stitches fully concealed. To assist in these operations of folding and sewing, various mechanisms have heretofore been proposed, and while such prior devices are of assistance in making a more uniform product, they are unduly complicated and expensive and require skill in their use and do not adequately speed up production.

The present invention has for its object the provision of a novel method of and apparatus for use in folding and stitching neckties of the class described, more particularly to provide a method whereby the operations of folding and stitching are greatly expedited as compared with prior practice but with assurance of equally good or better results and which can be carried out by relatively unskilled labor; to provide means whereby the folded tie may be transferred to the stitching mechanism without danger of disarrangement; to provide mechanism such that tacking stitches may be formed at a series of spaced points simultaneously thereby materially reducing the time necessary for stitching; to provide novel means for transferring the folded tie to the stitching mechanism such that each tie is delivered individually and immediately after folding to the stitching mechanism; to provide a simple form of holder for the folded tie; to provide simple control for the stitching mechanism, and in general to furnish novel and efficient means and method of accomplishing the desired result. Other and further objects and advantages of the invention will be pointed out in the following more detailed description and by reference to the accompanying drawings wherein:

Fig. 1 is a plan view, more or less diagrammatic in character, illustrating the associated folding and stitching mechanism in accordance with the present invention;

5 Fig. 2 is a front elevation of the mechanism of Fig. 1;

Fig. 3 is an end elevation, to larger scale, of the mechanism shown in Fig. 1;

10 Fig. 3a is a fragmentary edge elevation of an attachment to the feed slide of one of the sewing mechanisms;

Fig. 4 is a fragmentary plan view of the folding mechanism showing a necktie blank, of the kind employed in making a four-fold liningless tie, arranged in preparation for the folding operation;

15 Fig. 5 is a fragmentary section to large scale substantially on the line 5—5 of Fig. 4;

Fig. 6 is a plan view similar to Fig. 4 but showing the initial folding operation completed;

20 Fig. 7 is a view similar to Fig. 5 (being a section on the line 7—7 of Fig. 6), indicating the completion of the second step of the folding operation;

Fig. 8 is a view similar to Fig. 7 but showing 25 the folding operation completed and the folded tie blank in the holder;

Fig. 9 is a plan view of a simple form of holder for the necktie blank;

30 Fig. 10 is a section, to larger scale, substantially on the line 10—10 of Fig. 9;

Fig. 11 is a view similar to Fig. 9 but illustrating a modified form of holder;

Fig. 12 is a plan view of a necktie blank after 35 it has been folded and sewed but before turning;

Fig. 13 is a fragmentary plan view of the tie blank, to larger scale, showing the tacking stitches extending transversely of the tie; and

40 Fig. 14 is a view similar to Fig. 13 but showing the tacking stitches extending lengthwise of the tie.

Referring to the drawings, the numeral 1 designates a suitable bench upon which is mounted an elongate support 2 which carries various parts of the apparatus. This support may be made 45 of any suitable material, for example plywood or metal, and at one end portion carries the folding means within the "folding zone" designated F, Fig. 1, while at its opposite end there are arranged stitch-forming mechanisms within the "stitching zone" designated S, Fig. 1.

The support 2 is provided with a horizontal surface 3 upon which the necktie blank rests during folding and sewing. The support is also furnished with a downwardly inclined forward surface 4 (Fig. 3) upon which are located guide-

ways for the necktie blank holder. As indicated in Figs. 1 and 3, a guide member 5 extends from the folding zone into the stitching zone, said guide member being shaped to provide the guideway or slot 6 at its upper edge. A second guide 7 extends from the stitching zone into the folding zone and is shaped to provide the guideway or slot 8. The guide members 5 and 7 are so disposed that the parallel slots 6 and 8 are spaced sufficiently to permit a tie blank holder to move along the guideway 8 without interference with a holder moving, for example, in the opposite direction along the guide slot 6.

Within the stitching zone S there is arranged a plurality of stitch-forming mechanisms 9. The number of the stitch-forming mechanisms is an aliquot part of the entire number of stitches or groups of stitches to be formed in the necktie blank. As here shown, three such stitch-forming mechanisms are provided, and the tie blank is provided with 9 tacking stitches or groups of stitches. These stitch-forming mechanisms 9 may be of any suitable commercial type, those here chosen being button sewing machines of a well known make, slightly modified for the purpose of the present invention. Each of these machines comprises a sewing needle 10 together with the necessary adjunctive features (not here shown in detail) for making stitches, and each machine comprises a presser foot 11 and a feed slide 12. Each machine is provided with a suitable drive clutch (not shown in detail), each such clutch being controlled by a chain 13 (Fig. 3). The lower ends of these several chains are secured respectively to the upper ends of tension springs 14 whose lower ends are all attached to a single elongate rigid member 15 (Figs. 2 and 3) which is hinged at its rear edge at 16 so that its forward edge may swing up and down. A single chain 17 connects the forward edge of this swinging plate to a treadle 18 so that by depression of this single treadle all of the stitch-forming mechanisms may be started at the same instant. The several presser feet of the machines are connected to a lifting mechanism which is actuated by a chain 19 connected to a treadle 20 so that by depression of the treadle 20 the presser feet may all be lifted at the same time.

In accordance with the present invention, the feed dogs are removed from the several machines and replaced by thin, smooth surfaced flat bars 21 connected to the respective feed slides 12 so that the bars 21 vibrate from front to rear during stitch formation. The bars 21 of the right and left-hand machines of the group are furnished with upwardly directed hooks 22, Figs. 1 and 3a, designed to engage a tie blank holder, hereinafter described, and to vibrate the holder back and forth during the formation of the tacking stitches. The bar 21 of the central machine need not be provided with such a hook unless desired.

Within the folding zone F the upper surface of the support 2 is furnished with an elevated portion 23 (Figs. 5, 7 and 8) upon which is mounted a series of gauge members 24 (Figs. 1, 4 and 6) designed to engage the rear edge B' of the necktie blank in order to position the blank properly for folding. Upon this elevated surface 23 two brackets are mounted carrying hinges 25 to which is secured the presser member 26. This presser member is of thin, stiff sheet material, for example, thin metal, and is of a length corresponding to the necktie blank and has a forward edge 27 (Fig. 1) of curved contour corresponding to that

of the fold to be formed in the necktie blank. Since this member 26 is necessarily of thin material, it is preferred to stiffen it at its rear part by means of an elongate angle member 28. To this angle member is attached one end of a chain 29 which passes over a pulley 30 and then down below the bench 1 to a treadle 31 whereby the presser 26 may be swung upwardly about the hinges 25.

10 The apparatus comprises two or more (preferably a plurality) holders 32 (Figs. 9 and 10) designed to partake in the blank folding operation and to hold the folded blank during stitching. These holders may be made of any suitable material, but it has been found that sheet material formed from compressed fiber, for example, that known to the trade as "Prestwood" is desirable for the purpose since it is possible to make a holder very easily from such material at a low cost, and since a holder so made is sufficiently stiff, although light in weight, to perform the desired function. As illustrated more particularly in Fig. 9, this holder has the substantially straight rear edge 33, the parallel end edges 34 and 35, and the forward edge 36 which is curved to conform to the curvature of the fold to be made in the necktie blank. This curved forward edge 36 is provided with an inwardly directed slot 37. Conveniently, this slot may be a saw kerf and is of a depth inwardly of the edge 36 which may approximate, for example, from $\frac{1}{3}$ to $\frac{1}{2}$ the width of the neck band portion of the folded blank. By forming this slot as a saw kerf, its inner surfaces or walls are left somewhat rough and thus help frictionally to hold the necktie material which is forced into the slot. Preferably the slot is of a width approximating the normal uncompressed thickness of two plies of the necktie fabric, and preferably the slot flares at its outer end, forming smoothly rounded or beveled entrance surfaces at 38 and 39.

45 The under side of the holder 32 is provided with an elongate slot 40 for engagement by the hooks 22 of the sewing mechanisms, as above described.

50 If the roughness resultant from the formation of the slot 37 as a saw kerf is not sufficient for the purpose, it is contemplated that the holder 32a may be made as shown in Fig. 11. In this holder one or both walls of the slot 37 is provided with a lining of friction material 37a, for example, a textile pile fabric, sandpaper, or the like.

55 The support 2 within the folding zone F is preferably provided with an elongate front stop member 23a to assist in positioning the holder preparatory to the folding operation, and is likewise furnished with a guide member 28a for engagement with the end edge 35 of the holder.

60 In preparation for performing the folding operation, the presser 26 is raised by depression of the treadle 31 substantially to the position shown in Fig. 8. A holder 32 is then placed in the position shown in Figs. 5 or 8 with its rear edge resting against the stop 23a, and a necktie blank B (whose ends have previously been bound) is laid face upward upon the surface 23 of the support with its rear edge B' contacting gauges 24, and so as to overlie the upper surface of the holder 32. The presser 26 is now moved down upon the rear portion of the blank B and when it has reached a substantially horizontal position, the operator pushes the holder 32 rearwardly so that its beveled surface 38 engages the necktie material and pushes the latter rearwardly about the edge 27

of the presser 26. This results in forming a fold of the material within the slot 37 of the holder and forces the folded material deeply into the slot, this position of the parts being shown in Fig. 7. The forward edge portion of the necktie blank may be assisted in this turning rearwardly by the left-hand of the operator while the holder 32 is being moved rearwardly. While the parts are in the position of Fig. 7, the operator seizes the holder 32 and draws it forwardly until it again reaches the stop 23^a, but since the inner surfaces of the slot 37 are rough, while the surfaces of the presser are smooth, the folded blank is drawn off of the presser 26 and remains with its fold firmly held in the slot 37 of the holder. The operator now takes the holder with the folded blank therein and placing the rear edge of the holder 32 in the guideway 6 pushes the holder over toward the stitching zone. If it be assumed that a necktie has just been stitched at the stitching zone and removed from the holder, an empty holder will, at approximately the same time, be placed by the stitching operator in the guide slot 8 and moved by the operator toward the folding zone in readiness for a subsequent folding operation. The holder supplied with the folded tie is moved along the guide slot 6 into the stitching zone and until it engages a stop member P, Fig. 1. The stitching operator depresses the treadle 20 so as to raise the several presser feet, and taking the holder out of the slot 6 disposes it in the position shown in Fig. 3 with the free edge portions of the folded tie in proper position beneath the presser feet of the several machines. The presser feet are then permitted to descend and the operator depresses the treadle 18 so as to start all of the several machines into operation at the same instant. The needles descend and form the first stitch and then as they rise out of the work, the hooks 22 pull the holder rearwardly together with the necktie material so that when the needles again descend, they enter the fabric at a point forwardly of the point at which they first entered, the repetition of this operation resulting in the formation of bar-type stitches, such as illustrated in Fig. 12, extending transversely of the width of the fabric. After these stitches or a group of such stitches has thus simultaneously been formed at the several points S', Fig. 12, the operator again raises the presser feet and moves the holder to the left a proper distance, then allows the presser feet to descend and again starts the machine to form stitches at the points S², Fig. 12. The presser feet are then again raised and the operation repeated to form stitches at the points S³.

It will be noted that by thus simultaneously forming stitches at a plurality of points, the number of operations necessary to bar-stitch the tie is materially reduced, in this instance $\frac{1}{3}$ of the usual number of operations being all that is necessary.

Having thus formed all the requisite tacking stitches, the operator removes the holder from the hooks 22 and pulls the stitched tie out of the holder, the tie now being in readiness for the turning operation. The empty holder is placed in the groove 8 and slid back toward the folding zone where a folding operation has been going on simultaneously with the stitching operation. It has been found in practice that an operator can perform the stitching operation by the use of three stitching mechanisms at approximately the same speed that another operator in the folding zone can properly fold a blank. Thus, the oper-

ations of folding and stitching are carried on substantially without intermission, the tie proceeding from the folding zone along a path parallel to its length, and when it reaches the stitching zone, moves intermittently along a similar path so that the amount of necessary handling of the tie material is reduced to a minimum.

5 The tie thus above described would be a four-fold, liningless tie, but it is contemplated that a tie provided with a lining may be made in substantially the same manner, the lining being stitched to the blank prior to the folding operation.

10 When the tacking stitches extend transversely, as shown in Fig. 12, it may sometimes happen that under sufficient transverse tension such stitches may show in the completed tie. To avoid this it may be preferred to form the tacking stitches as shown at S¹¹ and S¹², Fig. 14, so that they extend lengthwise of the tie. To accomplish this it is only necessary to change the cams which form a standard part of the equipment of such button machines as those above described, so that the feed foot of the machine will move lengthwise 20 of the tie. With such an arrangement the stitches extend lengthwise of the tie instead of transversely.

15 While a desirable embodiment of the invention has herein been disclosed by way of example, it is to be understood that the invention is not necessarily limited to this precise embodiment of means but is broadly inclusive of all equivalents and modifications which fall within the terms of the appended claims.

25 We claim:

1. Apparatus of the class described comprising an elongate rigid support having a substantially horizontal upper surface and a downwardly inclined forward surface, folding means disposed upon the horizontal surface adjacent to one end of the support, stitching means disposed upon the horizontal surface adjacent to the opposite end of the support, a pair of elongate guides mounted upon the inclined forward surface of the support, and rigid elongate tie holders each designed to cooperate with the folding means to fold and receive a folded tie and to move along one of the guides from the folding to the stitching means, and to return empty along the other guide to the folding means, the guides and holders being so arranged as to permit holders to pass in opposite directions without interference.

2. Apparatus of the class described comprising a support having mounted thereon a plurality of stitch-forming mechanisms, said support having a surface for the reception of a tie blank holder, an elongate tie blank holder operative to receive and to hold the fold of a folded tie blank, the holder having an elongate slot therein, and two at least of the stitch-forming mechanisms each including a hook element releasably engageable with the slot in the holder and operative during the formation of stitches to vibrate the holder transversely of its length.

3. Apparatus of the class described comprising a support having mounted thereon a row of spaced stitch-forming mechanisms, said support having a surface for the reception of a tie blank holder, an elongate tie blank holder operative to receive and to hold the fold of a folded tie blank, the two endmost of said stitch-forming mechanisms at least, each including a vibratory work feed element provided with a hook and the holder being shaped for detachable engagement with said hooks so as to be vibrated by the stitch-forming

mechanisms, and means operative simultaneously to stop and to start the several stitch-forming mechanisms thereby concomitantly to form stitches at spaced points lengthwise of the tie blank carried by the holder.

4. Apparatus for folding and sewing a four-in-hand necktie comprising an elongate support having mounted thereon tie-folding means, the support also carrying, at a point spaced from the folding means, a plurality of spaced stitch-forming mechanisms in number an aliquot part of the total number of stitches to be formed in the necktie, means for starting and stopping the several stitch-forming mechanisms simultaneously, a guide extending from the vicinity of the folding means to the stitch-forming mechanism, a tie holder for receiving and holding a folded tie blank, said holder being constructed and arranged to cooperate with the folding means in folding the tie, the stitch-forming means including a vibrating holder actuator, and the holder having an element cooperable with said actuator whereby the holder with a tie mounted therein, after being moved longitudinally from the folding position to the stitching position, may be vibrated transversely of its length while the stitches are being formed.

5. Method of making a four-in-hand necktie which comprises as steps providing a fabric blank, folding the blank along a longitudinal line to form superposed plies, advancing the folded tie longitudinally into a stitching zone, causing the tie to vibrate bodily in a transverse direction while in the path of a sewing machine needle thereby to form bar type stitches, again moving the tie lengthwise to bring another point thereof into the path of the needle, and vibrating the tie transversely to form bar stitches at the latter point.
6. Method of making a four-in-hand necktie which comprises as steps providing a fabric blank, folding the blank along a longitudinal line to form superposed plies, advancing the folded tie longitudinally into a stitching zone wherein a plurality of sewing machine needles, spaced longitudinally of the tie, are simultaneously acting to form stitches, bodily vibrating the tie in a transverse direction whereby each needle forms bar type stitches extending transversely of the tie, and again moving the tie lengthwise whereby the needles are caused to form stitches at points spaced from those first formed.
